ADHESIVE TAB FOR ROLLS OF SHEET MATERIAL

Noel John Baker, London, England, assignor to Witton-James Limited, Wembley, Middlesex, England

Filed Nov. 12, 1970, Sér. No. 25,940

Claims priority, application Great Britain May 11, 1970

Term of patent 14 years

Int. Cl. D19—99

U.S. Cl. D59—2

FIG. 2.

FIG. 1 is a top plan view of an adhesive tab for rolls of sheet material showing my new design, the side opposite being substantially a mirror image thereof; and

FIG. 2 is an edge view thereof.

I claim:

The ornamental design for an adhesive tab for rolls of sheet material, as shown and described.
